WATCH BAND

Melvin Marwil, Detroit, Mich.

Application September 8, 1941, Serial No. 410,051

4 Claims. (Cl. 63—11)

This invention relates to wrist watch bands, and more particularly to watch bands of resilient construction adapted to be slipped over the hand and to take a shape corresponding to the shape of the wrist.

Heretofore resilient plastic watch bands have been employed, but it has been found that the plastic material most commonly used i. e. Vinylite causes a skin irritation, possibly due to lack of ventilation between the band and the wrist and partially due possibly to an allergic reaction in some people.

However, it is the object of this invention to employ a highly resilient plastic material for a watch band, but to use in combination therewith means for maintaining a spaced relation between the elastic band and the wrist in order to secure proper ventilation, and also to keep said band out of contact with the skin.

It is the further object of this invention to employ a plastic member coiled or otherwise disposed over the elastic band for covering the same and for maintaining a spaced relation between said band and the wrist of a wearer.

It is the further object of this invention to provide plastic means attachable to the ends of the elastic watch band for securing the same to a watch.

The invention relates to the various elements and their combinations as hereinafter described in detail in connection with the appended drawing of which:

Figure 1 is a perspective view of the watch band as applied to the wrist.

Figure 2 is an elevational view of the unexpanded watch band.

Figure 3 is an elevational view of the watch band in expanded position.

Figure 4 is a cross-sectional view on line 4—4 of Figure 2.

Figure 5 is an enlarged sectional view taken on the line 5—5 of Figure 3 and showing in dotted lines, the watch balls to which the ends of the watch band are secured.

The above drawing illustrates merely a preferable embodiment of this invention, it being understood that other similar constructions are equally adaptable within the scope of the invention as hereinafter set out in the following specification and claims.

In the drawing, the wrist watch band consists of a flat thin elastic member 11 made of a suitable elastic or resilient material such as Vinylite. Vinylite is a highly plasticized plastic ma-

terial having a substantially high tensile strength.

The member 12 is also made of plastic material, preferably cellulose acetate, and is coiled about the length of the elastic member 11 as shown in Figs. 2 and 3 of the drawing.

It is understood that the above material is merely a preferable embodiment and that any other suitable covering material may be employed.

Member 12 consists of a continuous tight coil obtained by winding the material on a spinning core on a lathe.

It will be understood that the exterior surface of the coiled member 12 is arcuate or curved whereby only point or line contact is made with the wrist of the wearer. The advantage of this resides in the fact that almost complete ventilation is obtained with no discomfiture.

Said coil however may be of any other suitable shape, or on the other hand may be merely a covering member through which the elastic strip 11 is longitudinally disposed.

In applicant's preferred embodiment said coil is heat treated to guarantee that its shape is maintained; and so coiled also has a certain amount of resiliency.

Watch securing means 13 and 14 are provided at opposite ends of members 11 and 12. The watch securing means may be made of a plastic material or any other suitable material such as, leather, fabric, etc. In attaching the watch securing means to the watch band, the member 13 is first looped about the last convolution of the coil member 12 and the free ends thereof passed about the end of the strip 11 to form loops 17 and 18 as shown in Figures 1 and 5 of the drawing. The ends of the member 13 are then secured to the strip 11 by means of staples 15. It is obvious that lines of stitching at this portion of the end members 13 and 14 could be effectively used to secure the various parts together. Thus it will be seen that the watch securing members 13 and 14 also serve as means for maintaining the coiled member 12 in place on the elastic strip 11.

As constructed a very neat appearing band is provided which is entirely resilient for slipping over the hand of a wearer but at the same time causes no discomfiture.

By providing a limited contact area in each loop of the coiled member 12 a substantial ventilating effect is obtained thereby assuring wearing comfort.

By the provision of a unitary elastic member

11 and the coiled member 12 it is seen that no mechanical adjustment is required and furthermore said band is adaptable to any shape of wrist.

It will be understood that members 13 and 14 may be otherwise constructed as long as suitable means are employed for securing the ends of the wrist watch band to the watch.

Having described my invention in detail, reference should now be had to the claims which follow for determining the scope thereof.

I claim:

1. A wrist band comprising a strap of elasticized plastic material, a coiled member longitudinally disposed around said strap, and watch attaching means secured to opposite ends of said strap, said watch attaching means also securing said coiled member in proper position on said strap.

2. A wrist band comprising a flat thin strap 20 of elasticized plastic material, a flat coiled mem-

ber disposed about said strap, and watch attaching means secured to the ends of said strap, said watch attaching means also securing the said coiled member in proper position on said strap.

3. A wrist band comprising a strap of elasticized plastic material, a coiled member disposed about said strap, said member comprising a flat series of convolutions extending substantially the length of said strap, and watch attaching means secured to opposite ends of said strap for engagement with a wrist watch.

4. A wrist band comprising a flat thin strap of elasticized plastic material, a coiled member disposed about said strap, said member comprising a series of flat convolutions extending substantially the length of said strap, and watch attaching means secured to opposite ends of said strap, said watch attaching means also securing said coiled member in proper position on said strap.

MELVIN MARWIL.
